UNITED STATES PATENT OFFICE.

SOLOMON MARKS, OF CINCINNATI, OHIO, ASSIGNOR TO POST & CO., OF SAME PLACE.

DESIGN FOR THE ORNAMENTATION OF HUB-BANDS.

SPECIFICATION forming part of Design No. 16,603, dated April 6, 1886.

Application filed December 26, 1885. Serial No. 186,817. Term of patent 3½ years.

To all whom it may concern:

Be it known that I, SOLOMON MARKS, of Cincinnati, Ohio, have invented and produced a new and useful Design for the Ornamentation of Carriage-Hub Bands, of which the following is a specification, reference being had to the accompanying drawing, which represents a perspective view of my design.

Heretofore hub bands have been ornamented with beads having a portion of their surface ornamented.

My invention consists in an ornamental strip representing lattice-work surrounding the body of the band. On each side of the strip, and at the inner end of the body are plain parallel beads.

a represents a hub-band, having parallel plain beads *b* surrounding its outer portion,

a plain bead, *d*, surrounding its inner portion, and an ornamental strip, *c*, representing lattice work between the parallel beads.

I claim—

The design for the ornamentation of a hub-band herein shown and described, the same consisting of the two parallel beads at the outer end, a parallel bead at the inner end, and a strip representing lattice-work between the beads at the outer end.

The foregoing specification of my invention signed by me this 18th day of December, A. D. 1885.

SOLOMON MARKS.
